Primary Examiner — Cynthia Underwood(74) *Attorney, Agent, or Firm* — Thompson Hine L.L.P.(57) **CLAIM**

The ornamental design for a fashion hook, as shown and described.

DESCRIPTION

FIG. 1 is a perspective view of a fashion hook showing one embodiment of our new design;

FIG. 2 is front elevation thereof;

FIG. 3 is a top view thereof;

FIG. 4 is a bottom view thereof;

FIG. 5 is one side view thereof;

FIG. 6 is another side view thereof;

FIG. 7 is a perspective view of a fashion hook showing another embodiment of our new design;

FIG. 8 is front elevation thereof;

FIG. 9 is a top view thereof;

FIG. 10 is a bottom view thereof;

FIG. 11 is one side view thereof; and,

FIG. 12 is another side view thereof.

The rear portion of the embodiments of the fashion hook are not visible during ordinary use and form no part of the claimed design.
